(57) **CLAIM**

The ornamental design for a compact male urinary catheter,
as shown and described.

DESCRIPTION

FIG. 1 is an isometric and exploded view of one embodiment
of a compact male urinary catheter;

FIG. 2 is a perspective view of a cap of the compact male
urinary catheter illustrated in FIG. 1;

FIG. 3 is a perspective view of a catheter of the compact male
urinary catheter illustrated in FIG. 1;

FIG. 4 is a perspective view of a container portion of the
compact male urinary catheter illustrated in FIG. 1;

FIG. 5 a front side view of the compact male urinary catheter
illustrated in FIG. 1, where a back side view is not illustrated
as it is a mirror image of the front side view;

FIG. 6 is a left side view of the compact male urinary catheter
illustrated in FIG. 1;

FIG. 7 is a right side view of the compact male urinary
catheter illustrated in FIG. 1;

FIG. 8 is a top side view of the compact male urinary catheter
illustrated in FIG. 1, where a bottom side view is not illus-
trated as it is a mirror image of the top side view;

FIG. 9 is an isometric view of the compact male urinary
catheter illustrated in FIG. 1 in an assembled state to show an
end of the cap;

FIG. 10 is a front side view of the compact male urinary
catheter illustrated in FIG. 9, where a back side view is not
illustrated as it is a mirror image of the front side view;

FIG. 11 is a left side view of the compact male urinary
catheter illustrated in FIG. 9; and,

FIG. 12 is a right side view of the compact male urinary
catheter illustrated in FIG. 9.

In FIG. 1-FIG. 8 the broken lines illustrate a urine collection
bag associated with the compact male urinary catheter and
form no part of the claimed design.

In FIG. 9-FIG. 10 the broken lines illustrate a seal placed
around the assembled compact male urinary catheter and
form no part of the claimed design.
